UNITED STATES PATENT OFFICE

116,677

DESIGN FOR A RECREATIONAL GAME TABLE

Ray Becker, Northbrook, Ill.

Application July 8, 1939, Serial No. 85,920

Term of patent 3½ years

To all whom it may concern:

Be it known that I, Ray Becker, a citizen of the United States, residing in Northbrook, in the county of Cook and State of Illinois, have invented a new, original, and ornamental Design for Recreational Game Tables, of which the following is a specification, reference being had to the accompanying drawing, forming part thereof.

The drawing is a perspective view of a recreational game table embodying my new design.

I claim:

The ornamental design for a recreational game table, as shown.

RAY BECKER.
